UNITED STATES PATENT OFFICE.

EARL F. OYSTER, OF EAST CLEVELAND, OHIO.

FORGING-PRESS.

1,094,092.

Specification of Letters Patent. Patented Apr. 21, 1914.

Application filed December 2, 1912. Serial No. 734,462.

To all whom it may concern:

Be it known that I, EARL F. OYSTER, a citizen of the United States, residing at East Cleveland, in the county of Cuyahoga and State of Ohio, have invented a certain new and useful Improvement in Forging-Presses, of which the following is a full, clear, and exact description, reference being had to the accompanying drawings.

10 This invention relates to presses of the type wherein the pressing head or die may be moved rapidly to the work and is then automatically submitted to an intensified hydraulic pressure, by means of a displacement plunger operated by steam pressure.

15 The object of the invention is to provide such a press, adapted for forging, which shall be rapid and effective in action, simple in construction, and durable in service.

20 The simplicity of my forging press renders it comparatively cheap to construct and prevents its getting out of order in use. Notwithstanding this simplicity and cheapness, my press is very efficient, the pressing die moving rapidly to its work and then delivering the desired intensified pressure, after which the parts return to normal position. The characteristics of the press by which I accomplish these results are herein- 25 after more fully explained and are definitely set out in the claims.

30 In the drawing, Figure 1 is a front elevation of my forging press; Fig. 2 is a side elevation thereof; Fig. 3 is an enlarged vertical section through the upper portion of the forging press; Fig. 4 is a sectional plan of a plane through the intensifying plunger; Fig. 5 is a detail in vertical section through the valve which controls the passage in the intensifying plunger, this section being central of the machine and in a plane parallel with Fig. 2; Figs. 6 and 7 are sectional details illustrating the valves for controlling the steam to the main steam cylinder and to the lifting cylinders for the movable die, respectively.

35 Referring by numerals to the parts shown in the drawings, 10 represents a suitable base which carries a block 11 on which is mounted the stationary pressure block or die 12. Rising from the base 10 and rigidly secured thereto are four vertical columns 14 secured at their upper ends to a stationary cross frame 15.

40 16 indicates a cross head, which is slidably mounted on the columns 14 and carries

the pressing head or die 18. It is to be understood that the work is placed between the dies 12 and 18, and then the die cross head 16 allowed to drop to bring the die 18 to the work, and then the intensified pressure is applied to the cross head 16, as hereinafter described.

45 Secured to the cross frame 15 on opposite sides thereof are the two cylinders 20. In these cylinders are pistons 21 connected by rods 22 with the die cross-head 16. The rods pass through stuffing boxes 23 at the lower ends of the cylinder. The upper ends of the cylinders are constantly vented, by ports 70 24, to the atmosphere, while the lower portions of the cylinders are connected to a steam pipe 30 which leads to a valve 31. This valve is adapted to put the pipe 30 in communication either with a live steam pipe 75 32 or an exhaust pipe 33. The valve is normally positioned to connect the pipes 30 and 32 so that the steam pressure is admitted to the cylinders 20 and acts upwardly on the under sides of the pistons 21 to support the 80 working cross head 16. When, however, the pipe 30 is coupled with the exhaust 33, the cross head, together with the piston and piston rods, descends by gravity, and this brings the pressing head or die 18 down 85 until it engages the work.

85 The cross head 16 is provided with an upwardly extending, hollow plunger 35 which slides within a cylinder 36 provided by and consisting of a portion of the cross 90 frame 15. A suitable packing prevents leakage between the piston and cylinder wall, as, for example, the stuffing box construction shown at 38. The cross frame 15 is shown as hollowed out for lightness, as appears in 95 Fig. 3. The cylinder 36 may constitute an integral portion of this cross frame and the cylinders 20 be bolted to it, as shown in the drawings.

100 The top wall of the cylinder 36 is extended and braced to form a horizontal platform 39, from which rise four vertical columns 40. Slidably mounted on these columns 40 is a cross head 41. This cross head carries a tubular plunger 42 extending 105 through a stuffing box 43 carried by the platform 39 into the cylinder 36 and the recess in the plunger 35. This plunger 42 is adapted, as hereinafter explained, to have its passageway closed during operation and thus 110 to displace a comparatively small quantity of liquid in the cylinder 36, and thus give

an intensified hydraulic pressure to the movable die.

The upper, or intensifier, cross head 41 is provided with an upwardly extending cylinder 45. Liquid is contained in the cylinder or reservoir 45, in the bore of the plunger 42, in the upper portion of the cylinder 36 and in the recess within the plunger 35. A valve, to be hereinafter described, in the tubular plunger 42 is normally open so that the liquid in the cylinder 36 is in open communication with the liquid in the cylinder 45. Accordingly, when steam is released from the lifting cylinders 20 and the working cross head 16 drops by gravity, liquid follows into the cylinder 36 from the reservoir 45. Now, will it be seen that if the valve in the tubular plunger 42 be closed, and that plunger, with its inclosed liquid, be forced downwardly into the cylinder 36, the desired intensified hydraulic pressure will be submitted to the cross head 16. Means for operating the intensifier plunger 42 will now be described.

The columns 40, on which the upper cross head 41 is slidable, carry at their upper end a steam cylinder 50. Mounted on opposite sides of this cylinder are lifting cylinders 51, within which are pistons 52 having piston rods 53 extending downwardly through the stuffing boxes 54 and connected at their lower ends with the cross head 41. The upper ends of the cylinders 51 are vented to the atmosphere as shown at 55. The lower portions of the cylinders 51 are adapted to be in communication with steam under pressure. I deem it preferable to keep them under constant steam pressure directly from the steam boiler, without the necessity of an intermediate valve, the area of the pistons 52 being sufficient to raise the intensifier cross head and attached parts when released. The steam connection to the cylinder 51 is illustrated by the pipe 57, which is connected with each of the cylinders and at its outer end connected with a live steam pipe 32, which is shown as connected with a main steam pipe 59.

Slidable in the reservoir cylinder 45 is a piston 60, which is shown as provided with adjustable packing and a packing ring 61 secured by bolts, as will be well understood. There is clearance open to the atmosphere between the outer wall of the cylinder 45 and the inner wall of the cylinder 50. Within the cylinder 50 is a piston 64. The two pistons 60 and 64 are rigidly connected together by a rod 65. Above the piston 64 the cylinder 50 is adapted to receive live steam. The cylinder is shown as provided with a port 66 connected with a pipe 67 which leads to a valve casing 68. A valve in this casing is adapted to put this pipe in communication with the main steam pipe 59, or in communication with an exhaust

pipe 69. Normally, the pipe 67 is in communication with the exhaust 69.

When the cylinders 20 are vented to allow the working cross head 16 to drop, it is preferable to open the valve in the casing 68 sufficiently to admit a small quantity of live steam above the piston 64. This allows the pistons 64 and 60 to move downwardly, as required to keep a continuous body of liquid between the under side of the piston 60 and the plunger 35.

I have referred to a normally open valve in the conduit of the intensifier plunger 42. This valve is shown in Fig. 5. As there shown, the plunger 42 has at its upper end an enlarged head 70, which is bolted; or otherwise secured to the under side of the upper cross head 41. This head 70 is preferably an integral portion of the plunger. In this plunger 42 is a continuous bore 71, the upper end of which is closed by a suitable plug 72. Extending laterally from this bore within the head 70 is a passageway 73, from which extends an upward passage 74 communicating with an opening 75 through the bottom wall of the cross head 41 into the reservoir 45. The annular edge at the junction of the passageway 73 and the bore 71 forms a valve seat, with which coacts a valve 77 adapted to control communication between the tubular plunger and the reservoir cylinder 45.

The valve 77 has a stem 78 extending out through a stuffing box 79. It is shown also as provided with an opposed stem 80 guided in the bore of a plug 81 screwing into the head 70. The stem 78 slides through a suitable guiding bracket 83 and is connected at its end with a rock arm 84. This arm is on a rock shaft 85 journaled in ears on the cross head 41. Projecting from the rock shaft is a short rock arm 86, which normally engages an abutment 87 on the under side of the stationary cylinder frame 50. A spring 88 surrounds the valve stem 78 and is compressed between the stationary bracket 83 and adjusting nuts 89 on the stem.

From the above described construction it will be seen that normally the abutment 87 holds the valve 77 away from its seat, leaving open communication between the reservoir cylinder 45 and the pressing cylinder 36. However, whenever the cross head 41 carrying the reservoir cylinder is forced downwardly, it carries the valve with it and thus lowers the rock arm 86 from the abutment 87, allowing the spring 88 to seat the valve 77, thus closing communication through the tubular plunger.

After the movable die has descended to the work, it is only necessary, to give the intensified pressure, to admit live steam above the piston 64 in a sufficient quantity. This live steam on the large area of the pis-

ton overcomes the live steam against the under side of the smaller areas of the pistons 52 and forces downward the piston 60. This movement, as explained, automatically causes the valve 77 to close, and continued downward movement of the piston 60 shoves ahead of it the cross head 41, the blocked liquid in the cylinder 45 acting simply as a distance piece between the piston 60 and the base of the cylinder 45. In this downward movement the water in the tubular plunger 42 acts also as a distance piece between the closed valve 77 and the lower end of the plunger. Accordingly, a displacement takes place of the liquid in the cylinder 36 corresponding to the size of the plunger 42 the same as if it were solid. This comparatively small displacement in the comparatively large cylinder 36 gives the intensified pressure to the cross head 16 and movable die 18, as will be well understood. By means of this intensifying pressure I am able to deliver a pressing force of several tons to the square inch with my machine constructed within reasonable compass.

At the end of the forging operation, the coupling of the steam pipe 67 with the exhaust, and the allowing of live steam to enter the lifting cylinders 20 restores the machine to normal position. The cylinders 51 being preferably in constant communication with the live steam their pistons act automatically to raise the upper cross head when the pressure is relieved from above the piston 64; and, coincidentally with such raising, live steam is admitted to the cylinders 20, then their pistons raise the working cross head 16.

Any suitable valves may be employed for effecting the operation. It is desirable, however, to couple the valves together and connect them with one operating lever, so that the movements may be most simply effected and no time will be lost between them. A convenient arrangement of valves for this purpose is shown in Figs. 1, 2, 3, 6 and 7.

Referring to Fig. 6, 68 indicates the casing of the valve for controlling the admission and exit of live steam to the main cylinder 50. This casing has a port 90 communicating with the pipe 67 and a port 91 communicating with the pipe 59 containing live steam. Within the cylindrical interior of the casing is a piston valve 92 having heads 93 and 94. This valve has a stem 95 extending out through a stuffing box 96 and connected with a lever 97, which is pivoted to a bracket 98 mounted on the valve casing. It will be evident that the piston valve balances itself; that the port 90 is normally in communication with the exhaust at the open end of the casing; that if the outer end of the lever 97 is drawn downwardly, the piston valve is raised to put the live steam port 91 in communication with the port 90.

The valve 31 controlling the exit and admission of live steam to the cylinders 20 is illustrated in Fig. 7 as a duplicate of the valve just described but inverted. In this valve the position of the piston to the ports is the reverse of the valve 68, that is to say in valve 31 the normal position is to connect the live steam with the cylinders 20. Briefly, in Fig. 7, there is the port 90^a connected with the cylinders, a port 91^a connected with the live steam pipe, two heads 93^a and 94^a on the valve, and a valve stem 95^a connected with a lever 97^a intermediately pivoted on a bracket 98^a.

The levers 97 and 97^a of the two valves are preferably connected by a rod 100 which leads downwardly to suitable operating mechanism, as, for example, to the rock arm 101 on a suitably pivoted rock shaft 102 which has an upstanding rock arm 103 constituting an operating hand lever. Suitable means, as a weight 105 on the lower end of the valve stem 95, provides for normally maintaining the rod 100 in its elevated position. This is the position shown in Fig. 3, and also in Figs. 6 and 7.

In operation, the lever 103 is simply pressed toward the machine, thus pulling down the rod 100 sufficiently to couple the cylinders 20 with the exhaust and to slightly open the pipe to the main steam cylinder, allowing a small quantity of steam to enter above the piston 64. This causes the cross head 16 and the die 18 to rapidly move downward to the work. Then the lever 103 is moved farther toward the machine, which movement entirely uncovers the port 90 so that a sufficient quantity of live steam is admitted above the piston 64 to force downwardly the upper cross head and the displacement plunger, thus giving to the work the hydraulic pressure desired. It will be seen that the reservoir cylinder 45, with its piston, passes entirely out of the cylinder 50. This allows convenient access to the packing ring 61 to adjust the packing. The various other stuffing boxes and packing devices in the machine are of easy access, as will be seen. To replenish any liquid that may be lost through leakage, I prefer to provide an opening 110 through the top 39 of the cylinder 36, Fig. 3. 111 is a check valve in this opening, and 112 a pipe leading therefrom to any suitable source of liquid under pressure.

It should be noted that, while the particular embodiment of my invention shown in the drawings is an efficient one, changes and modifications may be made therein without departing from my invention, as hereinafter claimed.

Having thus described my invention, what I claim is:

1. In a machine of the character described, the combination of a co-operating

cylinder and plunger, a tubular displacement plunger working in the chamber within the cylinder, a valve for controlling the passing through the displacement plunger, and means for forcing liquid through the plunger.

2. In a machine of the character described, the combination of a frame, a movable pressing head, a cylinder and plunger, carried one by the frame and the other with the head, a displacement plunger working in the chamber within the cylinder and having a bore through which liquid may be supplied to the cylinder, and means in the machine for forcing liquid through said bore.

3. The combination of a frame, a pressing head slidably guided thereby, a coöperating plunger and cylinder, one connected with the frame and the other with the head, a hollow displacement plunger acting into the chamber within the cylinder, and means for controlling and forcing liquid through the plunger.

4. The combination of a frame, a cylinder carried thereby, a cross head slidably guided by the frame and having a plunger working in said cylinder, a tubular displacement plunger slidable through the head of said cylinder, means for operating the displacement plunger, and means for forcing liquid through it.

5. The combination, with a frame, of a cross-head slidably guided thereby, a coöperating cylinder and plunger carried by the frame and cross head, a tubular displacement plunger operating into the chamber within the cylinder, a reservoir coupled with the plunger, means for forcing the liquid from said reservoir to the said chamber through the displacement plunger, means for operating the displacement plunger, and lifting cylinders carried by said frame, and having pistons with rods connected to said cross head.

6. The combination of a frame, a pressing head slidably guided thereby, a coöperating piston and cylinder, one connected with the frame and the other with the head, a tubular displacement plunger acting into the chamber within the cylinder, a piston and cylinder for forcing liquid through the plunger, a movable reservoir adapted to communicate with the bore of the plunger, a valve for closing the conduit through the displacement plunger, and means for moving the reservoir and displacement plunger as a unit.

7. The combination of a coöperating cylinder and plunger, a reservoir, a piston operating therein, a tubular plunger carried by the reservoir and slidably extending into said cylinder, and means for controlling the passage of liquid through the plunger.

8. The combination of a frame, a pressing head slidably guided thereby, a coöperating cylinder and plunger carried one by the head and the other by the frame, a movable reservoir cylinder, a piston operating therein, a tubular plunger carried by the reservoir cylinder and slidably extending into the cylinder first mentioned, and a valve for controlling the passage of liquid between said cylinders.

9. The combination of a frame, a pressing head, a cylinder and plunger carried by the frame and head, a hollow displacement plunger slidable into the interior of the cylinder, a cross head with which the displacement plunger is connected, a cylinder carried by the cross head and adapted to be in communication with the hollow plunger, and a piston working in the last mentioned cylinder.

10. The combination of a frame, a pressing head, a cylinder and plunger carried by the frame and head, a hollow displacement plunger slidable into the interior of the cylinder, a cross head with which the displacement plunger is connected, lifting cylinders connected with said cross head, means for moving the cross head, and means for blocking the passage of liquid through the hollow plunger.

11. The combination of a coöperating cylinder and plunger, a hollow displacement plunger slidable into the interior of the cylinder, a cross head with which the displacement plunger is connected, lifting cylinders connected with the cross head, a cylinder carried by the cross head and in communication with the hollow plunger, a piston working in the last mentioned cylinder, a valve for controlling the passageway from the reservoir cylinder to the lower cylinder, and means for automatically closing said valve when the hollow plunger descends.

12. The combination, with a cylinder and a coöperating plunger, of a hollow plunger movable into the space within the cylinder, a movable cylinder connected with said plunger and having its interior in communication with the bore of the plunger, a valve for controlling said passageway, a piston working in the last mentioned cylinder, a main cylinder, a piston therein, and a rod connecting the last mentioned piston with the piston first mentioned.

13. The combination, with a frame and a pressing head slidably guided thereby, of a cylinder and plunger carried by the frame and head, a hollow tubular plunger slidable into the interior of the cylinder, a movable reservoir connected with said hollow plunger, a valve for controlling communication between the reservoir and plunger, a piston working in the reservoir, an alined steam cylinder into which the reservoir may ex-

tend, a piston in the steam cylinder, and a rod connecting the piston in the steam cylinder with the piston in the reservoir.

14. The combination, with a frame and a pressing head slidably guided thereby, of a cylinder and plunger carried by the frame and head, a hollow tubular plunger slidable into the interior of the cylinder, a movable reservoir connected with said hollow plunger, a valve for controlling communication between the reservoir and plunger, a piston working in the reservoir, an alined steam cylinder into which the reservoir may extend, a piston in the steam cylinder, a rod connecting the piston in the steam cylinder with the piston in the reservoir, lifting cylinders on the outer sides of the main steam cylinder, pistons therein, and piston rods connected to the reservoir.

15. The combination, with a pressing cylinder and plunger, of means including a tubular plunger adapted to supply pressure to liquid within the cylinder, stationary guide rods, a cross head slidably guided by said rods, said cross head having a wall constituting a liquid reservoir which is adapted to communicate through the tubular plunger with the pressing cylinder, a valve for controlling such passage, a piston operating within the reservoir wall, a main cylinder and piston, the latter piston being connected with the piston of the reservoir, and means for moving the cross head in opposition to the main piston.

16. The combination, with a pressing cylinder and plunger, of means including a tubular plunger adapted to supply pressure to liquid within the cylinder, a cross head having a wall constituting a liquid reservoir which is adapted to communicate through the tubular plunger with the pressing cylinder, a piston operating within the reservoir wall, a valve for the conduit from the reservoir to the pressing cylinder, means tending to seat said valve, mechanism for holding the valve open, said mechanism acting against an abutment carried by a stationary part of the frame, and the rest of the mechanism being carried by the cross head, whereby when the cross head moves the valve automatically closes.

17. The combination, with a pressing cylinder and plunger, of means including a tubular plunger adapted to supply pressure to liquid within the cylinder, a movable reservoir connected with the tubular plunger, a valve for controlling the passageway from the reservoir through the plunger to the pressing cylinder, a steam cylinder, the wall of the reservoir extending into the main steam cylinder with clearance between them, a piston in the reservoir, and a piston in the steam cylinder connected with the piston in the reservoir.

18. The combination, with a pressing cylinder and plunger, of means including a tubular plunger adapted to supply pressure to liquid within the cylinder, a movable reservoir cylinder connected with the tubular plunger, a valve for controlling the passageway from the reservoir cylinder through the plunger to the pressing cylinder, a steam cylinder alining with the reservoir cylinder, the wall of the reservoir normally extending into the main steam cylinder but adapted to move out of it, a piston in the reservoir, an accessible gland for packing said piston, and a piston in the steam cylinder connected with the piston in the reservoir.

19. The combination of a frame, a movable cross head, a plunger and cylinder carried by the frame and cross head, lifting cylinders for the cross head, a main steam cylinder, a movable reservoir, a second cross head carrying the reservoir, a piston in the steam cylinder, a connected piston in the reservoir, a tubular plunger carried by the reservoir cross head and extending into the pressing cylinder, valves for controlling the admission of steam to the main steam cylinder and the exit of steam from the lifting cylinders, and means for concurrently operating said valves.

20. The combination, with a coöperating plunger and cylinder, of a main steam cylinder, a movable reservoir, a cross head carrying the reservoir, a piston in the steam cylinder, a connected piston in the reservoir, a tubular plunger carried by the reservoir and extending into the pressing cylinder, 100 and a replenishing pipe connected with the pressing cylinder.

21. The combination of an upright frame, a cross head slidably guided thereby, a cylinder carried by the frame, a coöperating plunger carried by the cross head, upright rods carried by the frame, an upper cross head slidable on said rods and having an upwardly extending reservoir, a plunger on the under side of said upper cross head extending into the cylinder which is carried by the frame, said plunger being tubular and adapted to establish communication between the reservoir and said cylinder, a valve for controlling the passage through the plunger, 110 a main steam cylinder carried by said rods, a piston in the reservoir, a piston in the steam cylinder, and means for connecting said pistons.

22. In a machine of the character described, the combination of a frame having upright members and a cross portion, a cross head slidably guided on said frame, said cross portion of the frame having a cylinder and said cross head a plunger operating in the cylinder, standards rising from the frame, a steam cylinder carried at the upper ends of said standards, a cross head

- slidable on said standards, a reservoir carried by the last mentioned cross head and extending upwardly toward the steam cylinder, a piston in said reservoir, a piston in the steam cylinder, a connection between said pistons, a tubular plunger carried by the upper cross head and extending through the top of the pressing cylinder into the space therein, and means for opening and closing the passageway for liquid from the reservoir to the pressing cylinder via the tubular plunger.
23. In a machine of the character described, the combination of a base, upright columns, a cross frame carried at the upper ends of said columns, a cross head slidably guided on said columns, said cross frame having a cylinder and said cross head a plunger operating in the cylinder, upright rods rising from the cross frame, a steam cylinder carried at the upper ends of said rods, a cross head slidable on said rods, a reservoir carried by said cross head and extending upwardly toward the steam cylinder,
- 25 a piston in said reservoir, a piston in the steam cylinder, a connection between said pistons, a tubular plunger carried by the upper cross head and extending through the top of the pressing cylinder into the space therein, a valve for opening and closing the passageway by means of the tubular plunger from the reservoir to the pressing cylinder, means tending to close said valve, and a rock arm connected with the valve mechanism and normally engaging an abutment on a stationary portion of the machine and serving to hold the valve open, whereby the valve automatically closes when the reservoir cross head moves the valve mechanism away from the abutment.
24. In a machine of the character described, the combination, with a cylinder and plunger, of means for supplying hydraulic pressure thereto comprising a tubular displacement plunger, a valve for controlling the passage through the plunger, and means for forcing liquid through the plunger.
25. The combination of a frame, a compressing head slidably guided thereby, a cylinder and plunger carried by the frame and head, means for supplying hydraulic pressure to the cylinder and plunger comprising a hollow displacement plunger, means for forcing liquid through it, a valve for controlling the passage through the plunger, and means for automatically closing said valve when the displacement plunger moves.
26. The combination of a frame, a compressing head slidably guided thereby, a co-operating cylinder and plunger carried one

by the head and the other by the frame, a movable reservoir, a piston operating therein, a tubular plunger movable with the reservoir and adapted to communicate therewith and supply pressure to the cylinder and piston, and a valve for controlling the passage of liquid from the reservoir through the tubular plunger.

27. The combination of a frame, a compressing head, a cylinder and plunger carried by the frame and head, means including a hollow displacement plunger adapted to supply pressure to the liquid in said cylinder, a cross head with which the displacement plunger is connected, a cylinder carried by the cross head and adapted to be in communication with the hollow plunger, and a piston working in the last mentioned cylinder.

28. The combination, with a cylinder and coöperating plunger, of means for supplying hydraulic pressure thereto including a tubular plunger, a movable cylinder connected with said tubular plunger and having its interior in communication with a bore thereof, a valve for controlling the passageway through such bore, a piston working in the last mentioned cylinder, a main cylinder, a piston therein, and means connecting the last mentioned piston with the piston first mentioned.

29. The combination, with a cylinder and plunger, of means for supplying hydraulic pressure thereto including a hollow tubular plunger, a movable reservoir connected with said hollow plunger, a valve for controlling communication between the reservoir and hollow plunger, a piston working in the reservoir, an alined steam cylinder into which the reservoir may extend, the piston in the steam cylinder, and a rod connecting the piston in the steam cylinder with the piston in the reservoir.

30. The combination, with the cylinder and plunger, of means for supplying hydraulic pressure thereto including a hollow tubular plunger, a movable reservoir connected with said hollow plunger, a valve for controlling communication between the reservoir and plunger, a piston working in the reservoir, a steam cylinder, a piston therefor connected with the piston in the reservoir, and a lifting cylinder having a piston connected with the reservoir.

In testimony whereof, I hereunto affix my signature in the presence of two witnesses.
